(57) **CLAIM**

The ornamental design for dental model base having two rows of stationary pins for random location of teeth, as shown and described.

DESCRIPTION

FIG. 1 is a perspective view of the present invention.

FIG. 2 is a top plan view of the present invention.

FIG. 3 is a bottom plan view of the present invention.

FIG. 4 is a front elevation view of the present invention.

FIG. 5 is the rear elevation view of the present invention.

FIG. 6 is side view of the present invention; and,

FIG. 7 is a side view of the present invention.

UNITED STATES PATENT AND TRADEMARK OFFICE
CERTIFICATE OF CORRECTION

PATENT NO. : Des. 469,537 S
DATED : January 28, 2003
INVENTOR(S) : Huffman

Page 1 of 1

It is certified that error appears in the above-identified patent and that said Letters Patent is hereby corrected as shown below:

Title page,

Item [76], Inventor, "P.O. Box 1328, Sapulpa, OK (US) 74066" should read -- Oro Valley, AZ (US) --

Item [56], **References Cited**, Foreign Patent Documents, "GB 866118 1/1962" should read -- GB 886,118 1/1962 --

Signed and Sealed this

Twenty-ninth Day of July, 2003

JAMES E. ROGAN
Director of the United States Patent and Trademark Office
